COCKTAIL STIR STICK

Howard E. Barrows and Richard J. Berglund, Racine,
Wis., assignors to Tenneco Inc., Racine, Wis.

Filed Dec. 17, 1973, Ser. No. 425,112

Term of patent 14 years

Int. Cl. D7—06

U.S. Cl. D7—42

FIG. 1 is a side view of a cocktail stir stick showing our new design;

FIG. 2 is a front view;

FIG. 3 is a side view showing the side opposite that shown in FIG. 1;

FIG. 4 is a rear view;

FIG. 5 is a top plan view of the cocktail stir stick as shown in FIG. 4; and

FIG. 6 is a bottom plan view of the cocktail stir stick as shown in FIG. 4.

We claim:

The ornamental design for a cocktail stir stick, substantially as shown.
